US0D1031750S

(12) **United States Design Patent** (10) **Patent No.:** **US D1,031,750 S**
(45) **Date of Patent:** **** Jun. 18, 2024**

(54) **DISPLAY SCREEN OR PORTION THEREOF WITH GRAPHICAL USER INTERFACE**

(71) Applicant: **GE Precision Healthcare LLC**, Waukesha, WI (US)

(72) Inventor: **Chelsey Lewis**, Waukesha, WI (US)

(73) Assignee: **GE PRECISION HEALTHCARE LLC**, Waukesha, WI (US)

(**) Term: **15 Years**

(21) Appl. No.: **29/878,753**

(22) Filed: **Jun. 27, 2023**

Related U.S. Application Data

(62) Division of application No. 29/866,540, filed on Sep. 16, 2022, now Pat. No. Des. 994,703, which is a division of application No. 29/715,166, filed on Nov. 27, 2019, now Pat. No. Des. 965,614.

(57) **CLAIM**

The ornamental design for a display screen or portion thereof with graphical user interface, as shown and described.

DESCRIPTION

FIG. 1 is a front view of a display screen or portion thereof with graphical user interface according to the claimed design.

FIG. 2 is a rear view of the display screen or portion thereof with graphical user interface.

FIG. 3 is a top view of the display screen or portion thereof with graphical user interface.

FIG. 4 is a bottom view of the display screen or portion thereof with graphical user interface.

FIG. 5 is a left side view of the display screen or portion thereof with graphical user interface.

FIG. 6 is a right side view of the display screen or portion thereof with graphical user interface.

The dash-dot-dash broken lines showing the display screen and the dash-dash broken lines in the drawings showing the display screen portion and graphical user interface illustrate portions of the display screen or portion thereof with graphical user interface that form no part of the claimed design.

1 Claim, 6 Drawing Sheets
